UNITED STATES PATENT OFFICE.

EARL J. W. RAGSDALE, OF THE UNITED STATES ARMY, ASSIGNOR TO UNITED STATES ORDNANCE COMPANY, OF WASHINGTON, DISTRICT OF COLUMBIA, A CORPORATION OF VIRGINIA.

HAND-GRENADE.

1,306,718.

Specification of Letters Patent. Patented June 17, 1919.

Application filed May 25, 1916, Serial No. 99,836. Renewed January 18, 1917. Serial No. 143,186.

To all whom it may concern:

Be it known that I, EARL J. W. RAGSDALE, a lieutenant in the United States Army, at present stationed in the city of Washington, District of Columbia, have invented certain new and useful Improvements in Hand-Grenades; and I do hereby declare the following to be a full, clear, and exact description of the invention, such as will enable others skilled in the art to which it appertains to make and use the same.

My invention relates to hand grenades.

Broadly speaking, it is the purpose of my invention to reduce the danger of premature explosion in handling and throwing grenades by providing an improved safety device for normally holding the firing mechanism of the grenade inactive, said device being so arranged and positioned as to be directly engaged and actuated by the hand in the act of throwing the grenade.

Furthermore, it is my purpose to provide a safety device for grenades the construction and arrangement of which is such that the gripping action of the hand during the first portion of the throwing movement tends to force the safety device in a direction opposite to its release movement and thereby intensify its safety characteristics; while release movement of the device is effective by the natural or involuntary tendency of the hand to rotate the grenade at the termination of the act of throwing so that the release of the safety device can only occur as the grenade leaves the hand.

More specifically it is my purpose to provide a safety device for the firing mechanism of grenades in the form of a restraining detent which is removably engaged with the body of the grenade and so positioned and constructed as to be involuntarily withdrawn from the grenade by one or more fingers as the grenade leaves the hand in the act of throwing same.

I will disclose my invention in the best forms known to me at present and as applied to a hand grenade employing a time firing mechanism, but it will be apparent that the invention can be applied to grenades of the impact type and that it is susceptible to changes in forms and proportions and to

desirable additions with the exercise of only ordinary mechanical skill without departing from the spirit of the invention.

In the drawings chosen to illustrate my invention, the scope whereof is pointed out in the claims—

Figure 1 is a longitudinal section of my improved grenade, the firing mechanism being in restrained or inactive position;

Fig. 2, a section on the line 2—2 of Fig. 1;

Fig. 3, a view looking at the top of Fig. 1 with the spring cover for the fuse cavity in open position;

Fig. 4, a view looking at the right hand side of Fig. 1;

Fig. 5, a section on the line 5—5 of Fig. 1;

Figs. 6, 7 and 8 are perspective views showing successive conditions existing in throwing the grenade;

Fig. 9, a longitudinal section of a grenade showing a modified form of my invention, and

Fig. 10, a view looking at the right hand side of Fig. 9.

Referring to the drawings and particularly to Figs. 1 to 8 inclusive A indicates the body of the grenade which is of hollow construction and includes a chamber 10 for the bursting charge and a chamber 11 in which is mounted a portion of the firing mechanism. The chamber 11 opens at one end through the wall of the body A while the other end of said chamber is connected by a passage 12 with one end of a recess 13 formed in the body A and extending longitudinally of the latter. The other end of the recess 13 is connected with the chamber 10 by a passage 14 and this passage aligns with an opening 15 in the opposite wall of the body A. The wall of the body A is also provided with an opening 16 closed by a cap or plug 17 and through which opening the chamber 10 is supplied with the necessary charge of explosive. A tubular member 18 has one end threaded in the opening 15 and its other end reduced and engaged in the passage 14. Disposed within the member 18 is another tubular member 19 one end of which is engaged in the reduced portion of the member 18 while its other end is supported by a disk 20 mounted in the member

18. A suitable booster charge 18' is carried by the member 18 and surrounds the member 19. Before throwing the grenade a detonator 21 is inserted in the bore of the member 19 through the opening 15 and the latter is then closed by a cap or plug 22 threaded therein and which has a reduced extension 23 projecting into the adjacent end of the member 19. Mounted in the recess 13 in line with the chamber 11 is a container 24 carrying a friction primer 25. This container 24 embodies a lateral extension 26 in which is crimped or otherwise suitably secured one end of a fuse 27 which seats in the recess 13. The other end of this fuse extends into the passage 14 and into the adjacent end of the member 19, its terminal being disposed in correct operative relation to the detonator 21. The body A is provided with an annular flange or nipple 28 disposed concentric with respect to the chamber 11 and interrupted by the recess 13. Threaded on this flange is closing cap 29 which is applied after the fuse 27 and the firing mechanism of the grenade are inserted in the body. This cap 29 serves to lock a spring cover 30 in place in covering relation to the recess 13. One end of this spring cover 30 is secured to the body A by a pin 31 which permits pivoting of the cover. The free end of the cover is reduced as at 32 and is engageable between the ends of the flange 28 to hold the cover against pivotal movement. To open the cover it is necessary to first remove the cap 29 and then spring the free end of the cover outwardly to disengage same from the flange when it can be moved to the position shown in Fig. 3 to permit the insertion of the necessary parts in the body A. It will be noted that the cover 30 is narrower than the recess 13 so that when the cover is closed a suitable vent is provided to permit the proper burning of the fuse 27. Slidably mounted in the passage 12 is a firing rod 33 which carries on the end thereof disposed within the chamber 11 a head 34. The end of the rod 33 remote from the head 34 is embedded in the friction primer 25 and provided with serrations 35 whereby sudden longitudinal movement of the rod 33 in the direction of the open end of the cavity 11 will ignite the friction primer 25 and this will in turn ignite the time fuse 27 to explode the grenade. Slidably mounted in the cavity 11 is a plunger 36 having an axial passage 37 through which the rod 33 slides. This plunger is normally urged in the direction of the head 34 by a spring 38 and is restrained or held inactive by a detent B. This detent is substantially U-shaped and includes arms 39 and 40 and an arm connecting portion 41. The free ends of the arms 39 and 40 are contracted and removably engaged in recesses 42 respectively formed in the body A. When the arms 39

and 40 are engaged in the recesses 42 as shown in Fig. 2 they also engage in a circumscribing groove 43 on the plunger 36 and thus serve to hold the plunger in inactive position until the detent B is withdrawn. A removable safety pin 44 bridges the cavity 11 and is disposed in the path of movement of the rod 33 so as to prevent any firing movement of said rod until said pin is withdrawn just previous to throwing the grenade. It will be observed that a relatively large portion of the detent is disposed exteriorly of the body A and to prevent accidental disengagement of the detent guard ears 45 are formed on the body A and disposed on either side of the detent. 70 75 80

In throwing the grenade the safety pin 44 is first removed and the grenade gripped in the hand with one or more fingers bearing against the arm connecting portion 41 of the detent B as shown in Fig. 6. When so held the gripping action of the hand tends to force the detent B in a direction opposite to the movement necessary to effect its withdrawal and in this way I intensify 90 the safety characteristics of the detent by involuntary conditions existing in the first portion of the act of throwing the grenade. When the arm reaches the limit of its throwing movement the hand and the grenade will assume the relation shown in Fig. 7, the finger engaging beneath the arm connecting portion 41. In this status the grenade has just been whipped or released from the hand and involuntary tendency to rotate the grenade 100 at such time has moved the finger beneath the arm connecting portion 41 when further movement of the grenade in flight will cause the finger to withdraw the detent and arm the grenade as clearly shown in Fig. 8. 95 105

In the modified form of the invention shown in Figs. 9 and 10 I secure the firing mechanism in inactive position by means of a sear C which is pivoted on the body A and includes angularly disposed arms 46 110 and 47 the former of which is adapted to engage the head 34 and plunger 36 to hold the firing mechanism inactive. The other arm 47 of the sear C engages in an opening 48 of a spring trigger arm 49 mounted on 115 the body of the grenade and when said arm 47 is thus engaged it will be obvious that pivotal movement of the sear C to release the firing mechanism is impossible. A removable safety pin 50 is mounted in the 120 body A and cooperates with the arm 46 of the sear to also hold the latter against pivotal movement. This pin 50 is withdrawn just previous to throwing the grenade.

In throwing the grenade constructed as 125 shown in Figs. 9 and 10 a finger of the hand is engaged over the free end of the spring trigger arm 49 and as a result of the natural tendency to rotate the grenade as it leaves the hand said trigger will be flexed so 130

as to disengage same from the arm 47 and thus release the firing mechanism of the grenade for automatic action. It will also be observed that the gripping action of the 5 hand during the first portion of the act of throwing will tend to force the trigger 49 in a direction opposite to its release movement and thus intensify the safety characteristics thereof.

10 It will be noted I have previously stated that the invention can be applied to grenades of the impact type. In grenades of this type the actual operation of the firing mechanism does not take place until the impact of the grenade against an object occurs. In other words, up to the moment of impact, the firing mechanism of the grenade is simply armed. When the invention is employed in connection with this type of 15 grenade the activity of the firing mechanism is prevented, as the result of the influence of any releasing force by the safety device, and such safety device is released by the tendency to rotate the grenade in the act 20 of throwing same so as to permit subsequent activity of the firing mechanism to occur when the grenade strikes an object.

When I set forth in the claims that the safety device normally locks the firing 30 mechanism against activity and is released by the tendency to rotate the grenade in the act of throwing the same to permit activity of the firing mechanism I mean that such activity of the firing mechanism may occur 35 immediately upon the release of the safety device or may occur at a subsequent time when the grenade strikes an object.

I claim:

1. In a grenade, the combination of a 40 body, a firing mechanism carried by the body, a safety device normally locking the firing mechanism against activity and releasable by the tendency to rotate the grenade in the act of throwing the same to permit activity 45 of the firing mechanism.

2. In a grenade, the combination of a body, a firing mechanism carried by the body, and a releasable safety device normally holding the firing mechanism inactive, said device 50 being forced in the direction opposite to its release movement by the gripping action of the hand and involuntarily moved by the hand in the act of throwing the grenade to release the firing mechanism for activity.

55 3. In a grenade, the combination of a body, a firing mechanism carried by the body, and a safety device normally holding the firing mechanism inactive and operated by the hand in the act of throwing the 60 grenade to release the firing mechanism for subsequent activity, the relation of the hand with respect to the safety device during the initial portions of the act of throwing being 65 inoperative, and said relation involuntarily becoming operative during the final

portions of the act of throwing whereby said safety device is released by the movement of the grenade away from the hand.

4. In a grenade, the combination of a body, a firing mechanism carried by the body, and a safety device, said safety device including a detent normally locking the device in position to maintain the firing mechanism inactive, said detent being operated by the hand in the act of throwing 75 the grenade to release the safety device and permit activity of the firing mechanism, the relation of the hand with respect to the detent during the initial portions of the act of throwing being inoperative, and said 80 relation involuntarily becoming operative during the final portions of the act of throwing whereby said detent is operated to release the safety device by movement of the grenade away from the hand. 85

5. In a hand grenade, the combination of a body, a firing mechanism carried by the body, and a safety device normally holding the firing mechanism inactive and operated by the hand to release the firing mechanism 90 in the act of throwing the grenade, the relation of the hand with respect to the safety device during the initial portions of the act of throwing being inoperative, and said relation involuntarily becoming operative during 95 the final portions of the act of throwing whereby said safety device is released by the movement of the grenade away from the hand.

6. In a hand grenade, the combination of a body, a firing mechanism carried by the body, and a detent normally holding the firing mechanism inactive and operated by the hand to release the firing mechanism in 100 the act of throwing the grenade, the relation of the hand with respect to the detent during the initial portions of the act of throwing being inoperative, and said relation involuntarily becoming operative during 105 the final portions of the act of throwing whereby said detent is operated to release the firing mechanism by the movement of the grenade away from the hand. 110

7. In a hand grenade, the combination of a body, a firing mechanism carried by the body, and a safety device normally holding the firing mechanism inactive and actuated to release the firing mechanism by the tendency of the hand to rotate the grenade in the act of throwing same. 115

8. In a hand grenade, the combination of a body, a firing mechanism carried by the body, and a releasable safety device normally holding the firing mechanism inactive, said device being forced in a direction opposite to its release movement by the gripping action of the hand and involuntarily moved by the hand in the act of throwing the grenade to release the firing mechanism. 125

9. In a hand grenade, the combination of a body, a firing mechanism carried by the body, and a safety device normally holding the firing mechanism inactive, said device being forced in a direction opposite to its release movement by the gripping action of the hand and involuntarily moved by the hand in the act of throwing the grenade to release the firing mechanism. 130

a body, a firing mechanism carried by the body, and a releasable safety device normally holding the firing mechanism inactive, said device being forced in a direction opposite to its release movement by the gripping action of the hand during the initial portion of the act of throwing the grenade and involuntarily moved by the hand during the final portion of the act of throwing to release the firing mechanism.

10. In a hand grenade, the combination of a body, a firing mechanism carried by the body, and a detent removably engaged with the body and normally holding the firing mechanism inactive, said detent being withdrawn from the body to release the firing mechanism by the natural tendency of the hand to rotate the grenade in the act of throwing same.

11. In a hand grenade, the combination of a body, a firing mechanism carried by the body, and a detent removably engaged with the body and normally holding the firing mechanism inactive, said detent being forced in a direction opposite to its withdrawing movement by the gripping action of the hand during the initial portion of the act of throwing the grenade and involuntarily withdrawn from the body to release the firing mechanism by the hand during the final portion of the act of throwing.

12. In a hand grenade, the combination of a body, a firing mechanism carried by the body, and a U-shaped detent having its arms

removably engaged with the body and detachably interlocked with the firing mechanism to hold the latter in inactive position, the arm connecting portion of said detent being engaged by certain fingers of the hand whereby the natural tendency to rotate the grenade when throwing same will cause said fingers to engage beneath the arm connecting portion and withdraw the detent as the grenade leaves the hand.

13. In a hand grenade, the combination of a body, a firing mechanism carried by the body and including a spring impelled firing member, and a detent removably engaged with the body and detachably interlocked with the member to hold the latter in inactive position, said detent being withdrawn from the body to release the member by the natural tendency of the hand to rotate the grenade in the act of throwing same.

14. In a hand grenade, the combination of a body, a firing mechanism carried by the body, and a detent normally holding the firing mechanism inactive and moved to release the firing mechanism by the tendency of the hand to rotate the grenade in the act of throwing same.

In testimony whereof I affix my signature, in the presence of two witnesses.

EARL J. W. RAGSDALE.
